UNITED STATES PATENT OFFICE.

ROLAND E. HOWARD, OF WORCESTER, MASSACHUSETTS.

MASK.

1,286,326.

Specification of Letters Patent.

Patented Dec. 3, 1918.

Application filed April 13, 1918. Serial No. 228,295.

To all whom it may concern:

Be it known that I, ROLAND E. HOWARD, a citizen of the United States, residing at Worcester, in the county of Worcester and State of Massachusetts, have invented a new and useful Mask, of which the following is a specification.

This invention relates to a mask or blinder, and the principal objects thereof are to provide a construction which can be adjusted to fit the head of the wearer, but cannot readily be removed without destroying it so that it cannot be used a second time; thus securing a sanitary product that cannot carry disease or the like; to provide a construction of simple form which will be inexpensive to make; and to provide improvements by which the mask can be adjusted and yet not be removable, and other features of construction as will appear.

Reference is to be had to the accompanying drawings, in which—

Figure 1 is a front view of a mask constructed in accordance with this invention, showing its two strings extending therefrom;

Fig. 2 is a plan showing it in position to fit the head of the wearer;

Fig. 3 is an elevation of the adjustable fastening device;

Fig. 4 is a sectional view of the same, and

Fig. 5 is a view of a portion of the device showing how the mask is intended to be detached from the head of the wearer.

The principal use intended for this invention is to make masks or blinders for use in initiatory exercises and the like. Under present conditions these masks are used over and over again and can easily carry diseases, particularly diseases of the eyes. This invention is designed to prevent the reuse of a mask, and to provide a construction which will be cheap enough to permit of its being thrown away after being used once.

Referring to the drawings, it will be seen that the mask proper consists of an element 10 of well-known form, but preferably made of frangible material such as paper, but at any rate of sheet material. This has two strings 11 and 12 extending from it and preferably integral with it as shown, but at any rate formed of sheet material permanently attached to the mask proper and adapted to come together around the back of the head and have their ends attached to

gether to secure the mask on the head. One of these strings extends from one edge of the mask 10 without any special form of connection, but the other one is provided with rows of perforations 13 above and below it and with a tab 14 cut out from the material of the mask and located at the end of the string. This is to permit of this tab being pulled outwardly so as to tear it from the mask through said perforations, taking the string with it, thus rendering the mask incapable of being used again when it is removed.

For the purpose of connecting the strings together at the back, one of them is made plain and the other is provided with a connecting device 20 preferably of sheet metal and having one or more tongues 21 of flexible sheet metal preferably integral with the main portion thereof extending inwardly at a slant. This slant is toward the mask so that the end of the other string can be forced under these tongues and pulled up as tight as may be desired in order to securely fasten the mask on the head of the wearer, but if it is desired to pull the strings apart to detach the mask the tongues by their resiliency will engage the loose string and prevent its being drawn back in that manner. In order to make this action more efficient, the tongues can be provided with sharp serrations 22 on their edges if desired, as shown. The metallic member 20 is provided with projections 23 at its ends for fastening it to the string 12.

In the use of the device the mask is put in position and the strings brought around the back of the head of the wearer, and the end of the string 11 is forced in under the tongues 21 and its end drawn clear through the fastening device 20. It is then pulled up tight so that the mask will fit on the head and is then worn for any desired length of time. When it is desired to remove the mask a pull on either string will not accomplish this purpose except by breaking the string, and it is preferable to pull on the tab 14 and absolutely remove the string 11 from the mask.

It is to be noted that I prefer to make the mask tab 14 and strings 11 and 12 all of one piece of paper, although the strings can be permanently fastened on the mask if desired without departing from the scope of this invention as expressed in the claims, but in either event this entire mask is made

of cheap sheet material and is rendered sanitary by preventing its reuse.

Although I have illustrated and described only a single form of the invention, I am aware of the fact that modifications can be made therein by any person skilled in the art without departing from the scope of the invention as expressed in the claims. Therefore I do not wish to be limited to

10 all the details of construction herein shown and described, but what I do claim is:—

15 1. As an article of manufacture, a mask or blinder consisting of a piece of sheet material having strings extending from its opposite ends and a connection between one of said strings and the mask proper more readily frangible than the string or mask to localize the line of detachment.

20 2. As an article of manufacture, a mask or blinder consisting of a piece of sheet material having strings extending from its opposite ends formed of the same material and permanently connected therewith, and means on one of said strings for receiving the other and allowing it to pass through in one direction so as to tighten up the strings on the head of the wearer, but preventing its being moved in the opposite direction.

3. As an article of manufacture, a mask or blinder having strings extending from its opposite ends, and means on one of said strings for receiving the other and allowing it to pass through so as to tighten up the strings on the head of the wearer, but preventing its being moved in the opposite direction.

4. As an article of manufacture, a mask or blinder having strings extending from its ends, and a series of perforations arranged in rows on the two sides of one string so that that string can be readily detached from the mask to remove the mask and prevent its reuse.

5. As an article of manufacture, a mask or blinder having strings extending from its ends, and having a series of perforations arranged in rows on the two sides of one string so that that string can be readily detached from the mask to prevent the mask being used over again, and a tab at the end of said string to facilitate tearing the string away from the mask.

In testimony whereof I have hereunto affixed my signature.

ROLAND E. HOWARD.
